UNITED STATES PATENT OFFICE

JAMES L. BALTON, OF BALTIMORE, MARYLAND

BAKING AND MOLDING DEVICE

Application filed April 12, 1929. Serial No. 354,677.

The invention has for one of its objects to provide a mold and core structure for cup pastry making apparatus of the type especially designed for the manufacture of ice cream cones or similar cup pastry, the same being so designed and constructed and embodying such cooperation of parts, that the waste of batter is reduced to the minimum or it is entirely eliminated, so that perfect cones may be made.

Another object of the invention is to produce an improved molding device, whereby such articles may be molded and then baked, the improvements consisting mainly in the provision of an aluminium mold having cast therein rings of heavier and harder metal.

The use of aluminium molds and cores greatly reduces the amount of gas required to heat them to a baking temperature and in fact the gas required to heat aluminium molds is about one third less than that required to heat cast iron molds. But the use of all aluminium molds have proven very unsatisfactory because after little usage the aluminium wears to such an extent, due to the opening and closing of the molds and the insertion and withdrawal of the cores, that there is a poor cooperation between the parts. If the parts do not cooperate a large amount of batter is wasted and many imperfect cones are produced.

The apparatus constituting the present invention, embodies a female mold and a core of relatively light metal with a ring of heavier and harder metal cast in the mold and around the core. In its more subordinate nature the invention includes female mold and core constructed as aforesaid and having means of keeping the female mold in true alignment, that is, to prevent the central portion of a bank of female molds from bending outward, which would allow much batter to be wasted.

With the foregoing, and other objects in view, the invention consists of the novel con-

struction, hereinafter more specifically illustrated in the accompanying drawings, but it is to be understood that changes, variations and modifications may be resorted to without departing from the scope of the appended claims.

In describing the invention in detail, reference is had to the accompanying drawing which forms a part of the specification, and wherein like characters of references indicate corresponding parts throughout the several views, in which—

Figure 1 is a top plan view of the female molds.

Figure 2 is a side view of the molds with part broken away.

Figure 3 is a sectional view taken through one of the female molds.

Figure 4 is a sectional view of the mold core.

Figure 5 is a top sectional view of the female mold showing the reinforcing ring.

Figure 6 is a view of the reinforcing ring adapted to be secured around the core.

Referring to the drawings in detail 10 represents the aluminium female mold having sectional outer members 11 and 12 which may be provided with corrugations 13. The aluminium core 14 is constructed to shape the batter and form a cone of the shape of the core. In use the two outer mold sections 11 and 12 are connected together and then the batter is poured in any desired way into the batter cups 15, 16, 17, 18, and 19 thus formed. Insertion of the core 14 into the mold sections 11 and 12 serves to force the batter up the inner edges of these sections and thus form the material into the desired cone shape. The entire mold is then carried or moved in any desired way into a heating oven or heating furnace (not shown) and the batter then baked. When the mold first enters the heating oven it is necessary that the batter cups be opened sufficiently to permit the steam generated therein to escape. The rapid raising

75

80

85

90

and lowering the cores in the molds to permit the steam to escape causes excessive deterioration of aluminium molds unless they are equipped with rings of heavier and harder metal.

5 The batter cups formed by the connection of the mold sections 11 and 12 have throats 20 in which are placed iron or other hard heavy metal rings 21. Rings 21 are shaped as shown 10 at 22 in Figure 3 on the outer surface to receive rings 22' secured to the core head of the male core.

15 Rings 21 are provided with dovetail grooves 24 and studs 25 having heads 26 on the back side thereof so as to securely fasten the rings to the aluminium molds. By the use of the dovetail grooves and the studs rings will not become easily detached from the mold. The rings thus securely anchored in place become a permanent part of the mold.

20 Rings 21 are placed in casting rings or molds and the aluminium is then poured into the molds and when the aluminium becomes cooled the rings of heavier and harder metal are securely fastened to the aluminium mold sections and thus becomes an integral part thereof.

Figure 4 shows a core 14 which is provided 25 with iron or other similar metal ring 22' around the core head. Ring 22' has a web 23 which passes through the aluminium and thus holding the ring securely in place around the core head. The rings thus fastened to the core become a permanent part of the core.

30 35 The rings 22' of iron or other similar metal is placed in a casting ring and the aluminium is poured therethrough and then rammed into the ring. When the aluminium is cooled the rings are securely fastened to the head thereof.

40 45 To overcome the tendency of the aluminium molds from bowing outward in the middle there is secured to the sides of the mold section 11 and 12 bars 24 and 25 by bolts 26, 27, 28 and 29 which screw into studs 30, 31, 32, and 33, formed on the sides of the mold sections. Midway between the studs 30 and 31, 32 and 33 respectively is placed set screws 34 and 35 which may be tightened as much as is 50 necessary to keep the mold sections straight so that there is perfect cooperation between the parts.

55 What I claim is:

1. In an apparatus of the character stated, 60 an aluminium female mold having molding cavities closed except at the mouths of the cavities and having rings of heavier metal embedded in the aluminium near the open end of the cavities, aluminium cores adapted to enter and partly fill the molding cavities, said cores having rings of heavier metal secured around the upper large end, the rings adapted to rest upon the ring in the female molds when the cores are inserted into the 65 molds.

2. In an apparatus of the class described 70 an aluminium female mold having an iron ring securely attached in the open end of the mold; and an aluminium core adapted to enter and partially fill the mold, said core having an iron ring securely fastened near its upper end, said ring in the mold adapted to cooperate with the ring on said core in closing the mold to prevent the escape of batter.

75 3. In a baking apparatus, the combination 80 with an outer aluminium mold member having a ring of harder metal secured in the throat thereof, of an inner aluminium core member having a ring of harder metal secured around the head thereof and cooperating with said outer member to form a cupped batter product.

85 4. In a baking apparatus, aluminium mold units having a plurality of batter cups formed therein, said cups having iron rings 90 securely anchored in the open ends by means of dove tail grooves; aluminium cores adapted to enter the cups and shape the batter therein, said cores having iron rings securely anchored around the upper ends.

95 5. In a baking apparatus, a female mold having a plurality of cavities formed therein, bands of hard metal securely anchored in the throat of the cavities by means of grooves and studs; and aluminium cores constructed 100 to shape the batter in the cavities, said cores provided with bands of harder metal securely fastened around the upper ends.

105 6. In a device of the class described, 110 comprising an aluminium female mold unit provided with a plurality of cavities, said cavities having rings of harder metal securely anchored in the throat thereof; and aluminium cores constructed to shape the batter in the cavities, said cores having rings of harder 115 metal anchored thereto at the upper large ends.

120 7. In a baking apparatus for a cone baking machine; comprising a sectional mold provided with a plurality of cavities, bands of 110 harder metal secured in the throat of the cavities, cores for the sectional mold, said cores having bands of harder metal secured near the upper end of the cores by means of a web passing through the cores.

125 8. In a baking apparatus, an aluminium mold having an iron band secured in the open end by means of a dove tail groove, an aluminium core having an iron band secured around the head thereof by means of a web 120 passing through the core.

9. In combination with a sectional mold, an aluminium core having an iron ring secured around said core at a point below the upper end thereof.

10. In combination with a baking mold, of an aluminium core having a ring of harder metal secured around said core by means of a web passing through the core.

11. In an apparatus of the character de- 130

scribed an aluminium mold having molding recesses formed therein and members of harder metal secured around the mouth of each recess by means of dove tail grooves.

5 12. A cone baking apparatus comprising a sectional mold having a plurality of cavities formed therein; members secured in the throat of each cavity, said members of harder metal than the mold sections; cores for shaping the batter in the baking cavities, said 10 cores having bands of harder metal than the core securely fastened near the upper end of each core.
